UNITED STATES PATENT OFFICE.

POMPEIN BOSCH, OF ELGIN, ILLINOIS.

BORING-MACHINE.

1,314,181.

Specification of Letters Patent. Patented Aug. 26, 1919.

Application filed February 15, 1919. Serial No. 277,165.

To all whom it may concern:

Be it known that I, POMPEIN BOSCH, a citizen of the Republic of Hungary, residing at Elgin, in the county of Kane and State 5 of Illinois, have invented certain new and useful Improvements in Boring-Machines, of which the following is a specification.

My invention relates to boring machines and has for its primary object the provision 10 of an improved machine for boring out engine cylinders particularly the closely grouped cylinders of a gas engine casting.

Another object is the provision of improved means for centering the cutting tool 15 within the cylinder to be bored.

Another object is the provision of improved means for steadyng the cutting tool during the boring operation.

A further object is the provision of a novel 20 form of centering device applicable to one end of the cylinder to be bored and adapted to be moved from the cylinder by the tool carrier as the latter is fed through the cylinder, whereby the centering device is prevented from obstructing the completion of 25 the boring process.

A still further object is the provision of a novel form of frame work adaptable to an engine without its removal from the vehicle 30 in which it may be positioned, whereby the boring tool is accurately centered within the cylinder to be bored and is very rigidly supported therein.

Other objects and advantages of the invention will appear from the following description taken in conjunction with the accompanying drawings which form a part of this specification and illustrate the preferred embodiment of the invention.

40 In the drawings:

Figure 1 is a vertical longitudinal section through the plane defined by the axes of four automobile engine cylinders in a single casting, showing my invention in operative position 45 therein and partially sectioned in the said plane.

Fig. 2 is a section taken approximately on line 2-2 of Fig. 1.

Fig. 3 is a section taken approximately 50 on line 3-3 of Fig. 1.

Fig. 4 is a top plan view of a centering disk forming part of the present invention.

Reference numeral 10 indicates generally 55 a gas engine casting having the cylinders 11, 12, 13 and 14 and the water jacket 15. This casting 10 comprises the work to be operated

on, it being assumed that the cylinder 13 of the casting is to be bored.

At 16 is indicated the main frame member of my invention comprising preferably 60 a solid cylinder of iron having a diameter slightly less than that of the cylinder 12 in which it depends so that a slight space 17 is left between the wall of engine cylinder 12 and the wall of the main frame member 65 16. This main frame member is also somewhat shorter than the vertical length of the engine cylinder 12 so that its lower end does not reach quite to the bottom of the latter. A circumferential flange 18 is formed at the 70 upper end of main frame member 16 and rests upon the upper edge of the wall 19 of cylinder 12. An upper frame member 21 is fastened as by bolts 22 to the top of main frame member 16 and comprises an 75 arm 23 positioned to extend over the cylinder 13 to be bored, arm 23 terminating above cylinder 13 in a vertically drilled and tapped boss 24, boss 24 being eccentric with respect to the axis of cylinder 13. 80

The lower frame member of my invention is indicated at 25 and preferably comprises a short solid iron cylinder centrally bored for accommodation of a lag bolt 26 which has its upper end threaded into a center 85 tapped aperture provided in the bottom of the main frame member 16. The lower frame member carries an arm 27 spaced considerably below the casting 10 and carrying at its extremity a boss 28 positioned centrally below the axis of cylinder 13 and provided with a vertical bore 29 co-axial with that cylinder. A vertical shaft 31 is positioned at its lower end in bore 29 where it is secured by a set screw 32, the shaft projecting upwardly through and co-axial with cylinder 13 to a point somewhat above the upper surface of casting 10. 90

Space 17 provides a limited range of horizontal movement in the main frame member 100 16 whereby the lower frame member may be set to the exact center to be maintained in boring cylinder 13.

A rotatable tool carrier 33 is mounted on shaft 31 and at its enlarged lower end carries the cutting tool 34 which is adapted to follow a helical path from one end to the other of cylinder 13 in boring out that cylinder. 105

Tool 34 is set at an angle to the tangent 110 of cylinder 13 at the point of contact between the tool and the cylinder and is pref-

erably held in the carrier by means of a set screw 35.

A circular rack 36 concentric with shaft 31 is formed midway of the length of the 5 tool carrier 33 and above rack 36 the tool carrier is formed with an annular channel 37 in which is positioned a carrier supporting ring generally indicated at 38.

As stated the vertical bore of boss 24 in 10 upper frame member 21 is threaded and a power shaft 39 is threaded into this boss for vertical travel therein.

The power shaft 39 supports the tool carrier, rotates it and likewise feeds it longitudinally of shaft 31 during the cutting operation.

Formed on supporting ring 38 and projecting toward cylinder 12 is a vertically bored bearing lug 41, the bore of this lug 20 being co-axial with the bore of the boss 24 on the upper frame member. The bore of this lug is smooth and it is engaged by the smooth lower end of the power shaft 39, the thread of the power shaft terminating 25 at the upper end of lug 41. The lower end of the power shaft extends downwardly to the plane of the lower surface of the circular rack 36 and carries on its extremity and fixed thereto, a power pinion 42 meshed 30 with the rack 36. This pinion lies flush against the lower end of the lug 41 and the weight of the tool carrier is supported by the pinion 42 through lug 41 and ring 38. The upper end of the power shaft is 35 provided with an operating hand wheel 43, though, obviously, the shaft might be operated by connection with any convenient source of power other than the hand of the operator. As the tool carrier rotates 40 about shaft 31 it also turns within the supporting ring 38.

A lug 44, integral with lug 41, projects therefrom at right angles and into its vertical bore is rigidly fixed a brace rod 45 45 which parallels the power shaft 39 and fits snugly and slidably within a smooth vertical aperture provided in the lug 24 of the upper frame member.

Near its lower end the shaft 31 carries 50 a frusto-conical centering disk 46 which is closely fitted on the shaft but not so snugly as to prevent its sliding along the shaft. By engagement between the conical surface 47 of the disk and the sharp annular lower 55 edge 48 of cylinder 13 the shaft 31 is instantly centered in the cylinder. Coiled about shaft 31 is a helical spring 49 which is interposed between lower frame boss 28 and the centering disk to hold the disk up 60 against the cylinder edge during the assembly of the boring machine.

In assembling the boring machine on a cylinder casting (this invention being peculiarly adaptable to the boring of Ford engine cylinders) main frame member 16 is

snug by its flange 18 within cylinder 12 and lower frame member 25 is loosely secured to the main frame member by partially threading bolt 26 into the latter. Arm 27 is now swung to allow disk 46 to seat against the lower edge of cylinder 13 whereby the shaft 31 is centered in that cylinder. Upper arm 28 and upper frame member 21 are now lowered upon the main frame member, the tool carrier being simultaneously slipped 75 upon shaft 31, and bolts 22 are set, the main frame member, if necessary, being given such slight axial rotation as will bring bolts 22 into register with their tapped holes in the top of the main frame member. Bolt 80 26 is now set tightly, completing the assembly.

In the operation of the machine, and considering the tool carrier as starting from the upper end of shaft 31, the rotation of 85 power shaft 39 applies power to the tool carrier through pinion 42 and rack 36 to rotate the carrier, the gradual lowering of the power shaft through boss 24 feeding the tool downwardly as it turns. When the 90 tool carrier strikes the centering disk 46 the spring 49 yields and permits a sufficient depression of the disk as will allow the tool 34 to cut to the bottom of cylinder 13. Obviously any of the several cylinders of a casting may be similarly bored by setting the main frame member in the adjacent cylinder. For the purpose of assembling, the supporting ring 38 is made in 95 two parts as shown in Fig. 3. By means of a plurality of holes 51 the chips cut by tool 34 may be allowed to drop from the cylinder 13 in order that there shall not be a body of chips of uneven depth upon the disk to interfere with the depression of 100 the disk when the tool carrier approaches the lower end of the cylinder.

The function of the brace rod is to steady the tool carrier and tool against chattering, to lend support to the shaft 31 in a direction longitudinally of the cylinder casting, and to brace power shaft 39 in a direction transverse to the length of the cylinder casting, thus overcoming the tendency of the tool carrier and rack 36 to bend the power 110 shaft while the tool is cutting. Should it be necessary to replace tool 34 during the cutting operation, because of breakage, for example, it will be seen that the upper frame member and the power shaft and tool carrier may be removed for this purpose without disturbing the centered setting of the main frame member, the lower frame member and the shaft 31.

While I have illustrated and described 125 the preferred embodiment of the invention, it will be obvious that one skilled in the art may make modifications thereof without departing from the spirit of the invention. I wish, therefore, not to be restricted to the 130

precise embodiment shown, except in so far as the same is limited in the appended claims.

The upper surface 52 of the lower frame member 25 defines a plane standing exactly at right angles to the axis of the shaft 31. This surface 52 is placed in flat contact with the flat bottom surface of the cylinder casting 10 in centering the shaft 31 in cylinder 13. With these two surfaces in flat contact the shaft 31 is centered in cylinder 13 when the edge 48 of the cylinder is in contact all-around with the conical surface 47 of disk 46.

15 I claim:

1. In a machine for boring cylinder castings, the combination with a tool carrier shaft adapted to be positioned centrally within the cylinder to be bored, of devices 20 for centering said shaft, comprising a lower frame member in which the shaft is rigidly carried, said frame member having an upper surface defining a plane at right angles to the axis of the shaft, and a disk mounted on 25 the shaft and having a conical surface of sufficient diameter to contact with the lower edge of the cylinder to be bored.

2. In a machine for boring cylinder castings, the combination of a lower frame 30 member attachable to said casting and having a plane upper surface, a tool carrying shaft rigidly mounted on said frame member with its axis at right angles to said plane surface, the connection between the frame 35 member and the shaft being positioned below said plane surface, a centering disk concentrically mounted on the shaft and having an up-turned conical surface, and a spring interposed between said disk and 40 the frame member.

3. In a cylinder boring machine the combination with a tool carrier shaft extending rigidly and co-axially with a cylinder to be bored, of a tool carrier slidably and rotatably mounted on said shaft, an annular 45 rack formed on said carrier, there being an annular channel formed in the carrier in a plane parallel with that of the rack and at right angles to the axis of the carrier 50 shaft, a rigid frame having a tapped boss eccentrically positioned and spaced opposite an end of the cylinder to be bored, a power shaft threaded into said boss, adapted to travel therein, and overlapping the tool carrier, a pinion meshed with said rack and 55 fixed upon the end of power shaft, a supporting ring rotatably fitting the channel of the tool carrier, and a lug fixed upon said ring, bearing against one end of said pinion, 60 and rotatably fitted by a smooth portion of said power shaft.

4. In a boring machine, the combination with a rigid tool carrier shaft, of a tool carrier rotatably and slidably mounted 65 thereon, a circular rack formed on said

carrier, the carrier being provided with a peripheral channel, a rigid arm including a boss provided with a threaded aperture eccentrically positioned with respect to the tool carrier shaft and having its axis parallel thereto, a threaded power shaft engaging said boss aperture for travel therein, a supporting ring having a pivotal connection with said power shaft and slidably seated in said peripheral channel, and a 70 pinion fixed upon the power shaft and meshing with said circular rack, a fixed part of said ring bearing against one end of the pinion.

5. In a cylinder boring machine, the combination with a tool carrier shaft extending fixedly and co-axially through a cylinder to be bored, of a tool carrier rotatably and slidably mounted on said shaft, a tapped boss rigidly positioned opposite an end of 80 the cylinder to be bored and eccentric with respect to said shaft, a power shaft threaded into the boss for travel therethrough in a direction paralleling the tool carrier shaft, connections whereby at rotation of the power 85 shaft revolves the tool carrier, an apparatus engaging the tool carrier and power shaft whereby the axial travel of the power shaft feeds the tool carrier longitudinally 90 of its shaft.

6. In a cylinder boring machine, the combination with a tool carrier shaft concentrically fixed within the cylinder to be bored, of a tool carrier rotatably and slidably mounted thereon, a straight-tooth gear provided on the tool carrier, a supporting ring rotatably seated in a peripheral channel provided in the tool carrier, a rigid arm projecting radially from said ring and having an aperture paralleling the tool carrier 100 shaft, a stud rigidly projecting at right angles from said arm, a fixed frame member comprising a boss positioned opposite an end of the cylinder to be bored, and having a tapped aperture axially aligned with the 105 aperture of said rigid arm, there being also formed in said boss a smooth aperture having its axis parallel to the axis of said tapped aperture, a power shaft in threaded engagement with the tapped aperture of the 110 boss for axial travel therein, said power shaft having a smooth portion rotatably fitting the aperture of said rigid arm, a straight-tooth pinion fixed upon the power shaft and meshing with the circular rack 115 of the tool carrier, and a brace-rod slidably engaging the smooth aperture of said boss and having an end rigidly connected to said stud.

7. In a cylinder boring machine, the combination with a tool carrier shaft, of a frame comprising a fixed boss having spaced parallel apertures one smooth and one tapped 120 said apertures having their axes paralleling the shaft of the tool carrying shaft and ec- 125

centric thereto, the tool carrier slidably and rotatably mounted on the tool carrier shaft, a power shaft threaded for travel in the tapped aperture of the boss, connections between the power shaft and the tool carrier whereby the former rotates the latter, a supporting ring having rotatable engagement with the tool carrier, a brace-rod slidably fitting the smooth aperture of said boss, said brace-rod being rigidly connected to said supporting ring, and said power shaft being rotatable only with respect to said supporting ring and in pivotal connection therewith.

15 8. In a boring machine, the combination

with a frame member comprising an arm positioned opposite and spaced from an end of a cylinder to be bored, of a tool carrier shaft rigidly mounted on said arm and extending co-axially through said cylinder, a 20 centering disk slidably mounted on said shaft, a spring interposed between the arm and disk to seat the disk yieldingly against the end of the cylinder, and a tool carrier rotatably and slidably mounted within said cylinder upon the shaft. 25

In testimony whereof I have affixed my signature.

POMPEIN BOSCH.
